UNITED STATES PATENT OFFICE

CLAUDE F. TEARS, OF WEST NEW BRIGHTON, NEW YORK, ASSIGNEE, BY MESNE ASSIGNMENTS, TO THE TEXAS COMPANY, OF NEW YORK, N. Y., A CORPORATION OF DELAWARE

PROCESS FOR OIL DISTILLATION

Application filed April 23, 1923. Serial No. 633,820.

This invention relates to processes for the distillation of oils, and it has special reference to the continuous distillation of crude oil and the separation thereof into predetermined fractions or cuts by passing the evolved vapors successively through a series of insulated fractionating towers or columns that are preferably disposed the one above the other and so arranged that certain portions of the liquid condensed therein are delivered into the towers immediately below for further distillation or treatment.

One of the objects of the invention is to improve and simplify the construction and operation of systems of this general character and to provide a process and apparatus that is especially adapted for continuous and efficient operation and for the selective separation of the desired fractions or condensates through extremely close and accurate fractionation by means of fractionating bubble or boiling cap towers to produce fractions closely conforming to the desired boiling point ranges.

These and other objects and features of the invention will be more readily understood from the following description of an illustrative embodiment thereof shown in the accompanying drawings of which:

Fig. 1 and Fig. 1^a, taken together, diagrammatically constitute a view in side elevation, with certain portions broken away, of an apparatus constructed in accordance with the invention and particularly adapted for practicing the process involved, and

Fig. 2 is an enlarged sectional elevation of a portion of one of the combined heat exchangers and bubble tower units utilized in the system and process.

Referring to the drawings, the apparatus shown comprises, in general, a furnace 10 in which is mounted a still 12 containing a body of oil to be distilled; a plurality of insulated fractionating towers in the form of bubble towers 14, 16, 18 and 20 connected in series relation to the still and through which the evolved vapors are passed and fractionally separated; a plurality of heat exchangers 22, 24 and 26 that are associated and combined with the bubble towers 16, 18 and 20, respec-

tively, and through which the evolved vapors successively pass; a plurality of condensers 28 and 30 connected in series to the upper end of the last bubble tower 20 for condensing the lightest fraction; a residual oil draw-off line 32 for removing the heavy oils from the still; a charging line 34 for introducing fresh oil into the system; a heat exchanger 36 associated with the charging line and the residual oil draw-off line for effecting a heat exchange between the residual oil and the charging stock; a cooling device 38 for reducing the temperature of the residual oil emerging from the heat exchanger 36, and a plurality of cooling devices 40, 42 and 44 for reducing the temperature of the effluents or condensates removed from the lower ends of the respective bubble towers 16, 18 and 20.

The furnace 10 and the still 12 may be of any suitable and well known construction for effecting the distillation of a body of oil. The still is provided near its bottom with a pipe 46 by means of which steam may be introduced into the oil in accordance with usual practice.

As the distillation of the oil continues, it is desirable to draw off the heavy residual oil from the bottom of the still through the draw-off line 32 and inasmuch as fresh charging stock is preferably continuously admitted into the still, as will be hereinafter more fully described, the liquid level of the oil therein is maintained substantially constant by automatically withdrawing the residual oil from the bottom through the agency of an automatic float controlled valve 47 that is disposed in the draw-off line 32. The operation of this valve is effected and controlled by means of a suitable float 48 within the still, the movements of which are transmitted thereto through suitable mechanism 49. The automatic valve 47 is by-passed by a valve 47^a.

The draw-off line 32 delivers the heated residual oil into one end of the heat exchanger 36, comprising a casing 50 and a plurality of tubes 51 disposed therein. The heated oil traverses the tubes 51 and is discharged from the other end of the exchanger through a pipe 52 into the cooler 38 by means

of which the temperature of the residual oil is reduced before it is delivered through a pipe 53 to storage. The casing 50 of the heat exchanger 36 forms around the tubes 51 a jacket into which fresh charging oil is introduced through the charging line 34. During the traverse of the charging stock through the jacket of the heat exchanger, a transfer of heat is effected from the residual oil to the charging stock whereby said charging stock is preheated. This preheated charging stock emerges from the heat exchanger through the pipe 54, containing a valve 55, through which the oil may be delivered, if desired, directly to the still 12, although it is preferred to close the valve 55 and introduce the preheated charging oil through branch line 56 and valve 57 into the first bubble tower 14.

As the distillation of the oil in the still 12 proceeds, the evolved vapors are withdrawn through a vapor line 60 and delivered into the bottom of the first bubble tower 14, through which the vapors traverse in counter-current relation to the flow of the condensate accumulating within the tower and progressively gravitating towards its bottom. Such of the vapors as are not condensed in the bubble tower 14 pass on and are successively conducted through the remaining bubble towers 16, 18 and 20 and their associated heat exchangers 22, 24 and 26, while the lightest constituents, uncondensed in the towers, are carried through the condensers 28 and 30 and are finally collected.

The bubble tower 14 may be of any conventional construction, such as are common in the art. In fact, any form of fractionating towers may be used, although bubble towers are preferred. The bubble tower 14 as shown embodies a construction similar to that shown in the upper portion of Fig. 2, which illustrates one of the combined heat exchanger and bubble tower units employed in the system. The preferred construction of the bubble tower 14 will be understood from the following description of one of the combined exchanger and bubble tower units. These units are of like construction and a description of the first unit, combining the bubble tower 16 and heat exchanger 22, will suffice.

With particular reference to Fig. 2, the unit therein illustrated, comprises the bubble tower 16 which is disposed above and associated with the heat exchanger 22. The bubble tower embodies a plurality of sections or plates 64 that are disposed the one above the other and which communicate with one another by means of a series of upstanding vapor pipes 66, that are provided with caps 67 over their upper ends for the purpose of deflecting the vapors arising therethrough and directing them downwardly beneath pools of liquid oil 68 maintained therein.

The bottom edges of the caps 67 are preferably serrated to assist in effecting a uniform distribution of the vapors. In order to maintain a predetermined level of the pool 68 of liquid oil in each of the sections of the bubble tower, overflow pipes 69 are provided for delivering excess oil into the pools of oil in the sections below. From this construction, it will be understood that the vapors that are delivered to the bubble tower, or which are distilled from the portions of oil disposed therein, are caused to successively pass upwardly through the vapor pipes 66 and thence are directed downwardly by the caps 67, whence they emerge through the serrated edges thereof and bubble up through the pools of oil in the several sections. The heavier constituents of the vapors are condensed during this process, while the heat of the vapors assists in vaporizing or distilling off any lighter constituents contained in the pools of liquid. Any number of bubble tower sections may be employed, depending upon the character of the oil under treatment, the operating conditions, and the distillation range of the particular fraction or cut that it is desired to separate and collect as a condensate or effluent. It will be understood that the vapors tend to pass upwardly through the several pools of oil in the sections, and such of the vapors as are not condensed during this operation, accumulate at the upper end of the tower and are passed on for subsequent treatment in the next succeeding tower. On the other hand, the condensate that gradually accumulates in the several pools in the respective bubble tower sections progressively overflows and passes downwardly through the preceding lower sections.

The heat exchanger 22 is disposed directly beneath the lower section 64^a and comprises a casing 70 through which extend a plurality of vertical tubes 71 that are seated in the upper and lower plates 72 and 73. The upper ends of the tubes 71 open into and communicate with section 64^a immediately above them, while the lower ends thereof communicate with a section 74 disposed beneath the heat exchanger 22. The liquid oil which is delivered by overflow pipe 69 into the lower section 64^a of the bubble tower, is then permitted to flow downwardly through the various tubes 71 and into the lower collecting section 74, which is provided with a draw-off line 75 for the purpose of removing the condensate or effluent therefrom. In order to insure that the tubes 71 of the heat exchanger are filled with oil, the oil level is automatically maintained in the lower section 64^a above the upper ends of the tubes by means of float controlled valve 76 disposed in the draw-off line 75 and operated in accordance with the movements of a float 77 in any suitable manner.

The casing 70, enveloping the tubes 71 of the heat exchanger, forms a jacket into which vapors are introduced through a vapor line 78, the vapors passing around and in contact with the several pipes, being directed in their flow by a plurality of baffles 79 disposed within the casing. The vapors are conducted away from the heat exchanger casing by means of an outlet vapor line 80. During the traverse 5 of the vapors through the heat exchanger in contact with the tubes 71, some of the heat thereof is given up and absorbed by the liquid condensate contained in the tubes, while the temperature of the vapors is correspondingly 10 reduced. The heat thus absorbed by the condensate serves to vaporize certain of the lighter constituents thereof, which pass upwardly through the tower, depending, of course, upon their volatility. During this process, the 15 vapors within the casing lose some of their heat and certain constituents thereof are condensed and collect in the bottom of the heat exchanger from which they are drawn off 20 through a pipe 82 to serve as a reflux medium for the preceding bubble tower of the series. 25

Having this understanding of the construction and general operation of the individual bubble tower units, their arrangement and connection in the system will be set forth.

30 The vapor line 60 from the still 12 is connected to the lower section of the first bubble tower 14, whereby the evolved still vapors are delivered thereto and pass upwardly therethrough in counter-current relation to the 35 downwardly flowing liquid oil and condensate. As already stated, it is preferred to introduce the preheated charging oil through the line 56 into the bubble tower 14, and connections to the bubble tower may be effected 40 through either of the valved branch lines 83 or 84, depending upon which of the sections is to be utilized. Of course, certain of the lighter constituents of the charging oil will be vaporized in the residual oil heat exchanger 45 and such portions, upon entrance into the bubble tower rise through such of the remaining sections as their volatility will permit. The portions of the charging oil of lower volatility on the other hand, pass downwardly through the overflow pipes of the 50 various sections, being in part vaporized and in part raised to progressively higher temperatures as it gravitates to the lower end thereof. Such portions of the charging oil, 55 together with such condensate as may reach the lower end of the tower, is backtrapped to the still through the line 85.

The vapors that emerge from the top of the bubble tower 14 are carried through the 60 vapor line 78 leading to the heat exchanger 22 that is combined with the bubble tower 16 of the next succeeding unit. These vapors pass through the heat exchanger 22 in the manner already described and are thence delivered by the vapor line 80 to an interme-

diate enlarged section 64^b of the bubble tower 16. Such liquid oil as accumulates within the heat exchanger casing is run back through pipe 82 to the upper end of the preceding bubble tower 14 where it serves as a reflux 70 medium and mingles with the pool of oil in the upper section and is subjected to further treatment. The vapors entering the intermediate section 64^b of the bubble tower 16 either proceed in the manner already described through the upper section thereof or are condensed and gravitate downwardly through the lower sections and finally pass 75 through the exchanger pipes 71 to be ultimately withdrawn through the pipe 75 containing the automatic float operated valve 76, as one of the desired fractions, for instance, gas oil. This condensate fraction is reduced in 80 temperature by passing it through the cooler 40 and is thereafter collected or run to storage. 85

In a similar manner such vapors as emerge from the top of the bubble tower 16 are conducted by vapor line 88 to and through the heat exchanger 24 and bubble tower 18 of the next succeeding unit, which functions in a like 90 manner and produces a condensate fraction of the desired volatility, such as kerosene, which is drawn off and passed through the cooler 42 to storage. Such of the vapors as condense in the heat exchanger 24 are conducted through pipe 89 to the upper section 95 of the preceding bubble tower 16.

In an analogous manner the operation continues, and the vapors are passed through the succeeding unit which separates out the next 100 lighter fractional condensate or effluent, such as naphtha, which is drawn off and passed through the cooler 44 to storage.

Such of the oil vapors, as for instance gasoline, that emerge from the top of the last 105 bubble tower 20 of the series, are conducted through vapor line 90 into the upper end of the water-cooled condenser 28 through which they pass around the cooling pipes 91 and are thence conducted by vapor line 92 to the upper end of the water-cooled condenser 30.

Certain of the higher boiling constituents 110 of these vapors will condense in condenser 28 and are reintroduced into the top of the bubble tower 20 by means of pipe 93 for further treatment. The remaining vapors delivered to the condenser 30 are condensed therein and are withdrawn through the pipe 94 to storage as the final condensate or fraction, such as gasoline. The extremely light or wild 115 gases and vapors that are non-condensable in the condenser 30 may be taken off through pipe 95 and, if desired, passed through suitable scrubbers.

From the foregoing description, it will be 120 understood that a continuous process of distillation and fractional condensation is carried out in an extremely efficient manner to produce a plurality of cuts or fractions in the form of condensates or distillates that 130

are fractionated with extreme closeness and selectivity whereby the boiling point ranges of the various fractions closely conform to the desired and predetermined ranges.

5 While, for convenience, the invention has been described in connection with the distillation of crude oil and the selective separation of lubricating oil, gas oil, kerosene, naphtha and gasoline fractions, it will be understood that these terms are merely used in an exemplary manner and should not be literally construed as restricting the scope of the invention. Moreover, the details of construction, the arrangement and location of parts 10 and the mode of operation may be varied considerably within the spirit and scope of the invention and, therefore, only such limitations should be imposed as are indicated in the appended claims.

20 What I claim is:

1. A process of oil distillation that comprises distilling a body of oil in a still, passing the evolved vapors successively through a series of bubble towers for close fractionation and separation of predetermined condensates, continuously delivering fresh charging oil into the first bubble tower of the series, backtrapping into the still such of the charging oil and condensate as accumulates 25 at the bottom of the first bubble tower, effecting a heat exchange between the rising vapors and the gravitating condensate in transit between the other bubble towers to produce a reflux medium, removing said predetermined condensates from all but the first bubble tower of the series, and back-trapping to the preceding bubble tower to serve as a reflux medium therefor only the condensed vapors liquefied by said heat exchange.

40 2. A process of oil distillation that comprises distilling a body of oil in a still, continuously delivering oil to the still to maintain a constant liquid level therein, successively passing the evolved vapors through a plurality of bubble towers to effect a close fractionation thereof, back-trapping the condensate from the first bubble tower of the series to the still, passing the vapors emerging from each bubble tower of the series in heat 45 exchange relation with the gravitating condensate from the next succeeding bubble tower of the series to produce a reflux medium, drawing off the respective condensates from the several bubble towers except the first, passing the vapors uncondensed by the heat exchange into an intermediate point in the next succeeding bubble tower, and back-trapping only the condensed vapors liquefied by said heat exchange to the preceding bubble tower of the series to serve as a reflux medium therefor.

55 3. A process of oil distillation that comprises distilling a body of oil in a still, passing the evolved vapors successively through a series of fractionating bubble towers in

which predetermined fractions are separated, withdrawing hot residual oil from the still to maintain a substantially constant liquid level therein, passing the hot residual oil drawn from the still in heat exchange relation with the charging oil to preheat said charging oil, charging said preheated oil into the first bubble tower of the series, back-trapping into the still such of the charging oil and condensate as accumulates at the bottom of the first bubble tower, passing the vapors emerging from each bubble tower of the series in heat exchange relation with the gravitating condensate from the next succeeding bubble tower of the series to produce a reflux medium, separately drawing off the respective condensates from all but the first bubble tower of the series, passing the vapors uncondensed by the heat exchange into an intermediate point in the next succeeding bubble tower, and back-trapping only the condensed vapors liquefied by said heat exchange to the preceding bubble tower of the series to serve as a reflux medium therefor.

In witness whereof I have hereunto set 90 my hand this 14th day of April, 1923.

CLAUDE F. TEARS.
